DEHYDROHALOGENATION OF DIHALOPROPONIC ACID COMPOUNDS

William O. Ney, Jr., Somerset Center, Mass., assignor to General Aniline & Film Corporation, New York, N. Y., a corporation of Delaware

No Drawing. Application November 3, 1950,
Serial No. 194,018

8 Claims. (Cl. 260—486)

1

This invention relates to a process for the preparation of esters, amides and nitriles of α -haloacrylic acids by dehydrohalogenation of the corresponding esters, amides and nitriles of a dihalopropionic acid in which at least one of the halogens occupies the α -position; and it is an object of this invention to provide an improved process for such dehydrohalogenations.

More specifically, the invention relates to the preparation of esters of α -chloroacrylic acid by dehydrochlorination of the corresponding esters of α,β -dichloropropionic acid.

U. S. P. 2,245,547 to Pollack discloses dehydrohalogenation of dihalopropionic acid esters with sodium, potassium, calcium or magnesium hydroxides, carbonates or bicarbonates in the presence of water, preferably insufficient to form a solution of the alkaline dehydrohalogenating agent. However, this method has serious drawbacks in that the ester tends to saponify in the presence of the aforesaid alkaline reacting materials, and the process therefore requires that the alkaline dehydrohalogenating agent be added to the dihalopropionic acid ester at a rate substantially corresponding to that of the formation of the haloacrylic ester; further, that the α -haloacrylic ester produced be removed substantially as rapidly as it is formed from the reaction mixture, and that the amount of water present in the mixture be controlled to avoid an excess thereof. These conditions are difficult to maintain, and the process is therefore relatively unsuitable for commercial use.

I have discovered that the disadvantages of the aforesaid process are avoided by employing, instead of the alkaline dehydrohalogenating agents disclosed in the Pollack patent, an aqueous solution of an alkali metal monohydrogen phosphate as the dehydrohalogenation agent, especially in the presence of an alkali metal dihydrogen phosphate, whereby the aqueous reaction mixture acquires an acid reaction, e. g. a pH between 4 and 7 and preferably from 5 to 6, during all or almost all of the dehydrohalogenation.

One method of carrying out the process of my invention involves heating a dihalopropionic acid ester, amide or nitrile, as defined above, with an aqueous solution of an alkali metal monohydrogen phosphate (e. g. disodium hydrogen phosphate) in an amount corresponding to 1 to 3 mols per molecular equivalent of dihalopropionic acid in the dihalopropionic ester, amide or nitrile. During the initial stages of dehydrohalogenation (e. g. when the reaction has proceeded to the extent of 5 to 10% of completion), a sufficient

2

amount of alkali metal dihydrogen phosphate is formed to render the aqueous solution weakly acidic, and the major portion of the reaction thus takes place in an acidic rather than an alkaline dehydrohalogenating medium.

In a variation of the foregoing procedure, a minor proportion of an alkali metal dihydrogen phosphate (or a corresponding amount of phosphoric acid or another acid stronger than phosphoric acid or of comparable strength) is added to the alkali metal monohydrogen phosphate in the aqueous dehydrohalogenating reaction mixture, the amount of the dihydrogen phosphate or acid being sufficient to reduce the pH to less than 7 and preferably to about 6. A mixture containing 95 mol per cent of alkali metal monohydrogen phosphate and 5 mol per cent of alkali metal dihydrogen phosphate is suitable for this purpose. The aqueous dehydrohalogenation solution thus obtained is heated with a dihalopropionic ester, amide or nitrile, the proportions being such that at least 1 mol of alkali metal monohydrogen phosphate is present per molecular equivalent of dihalopropionic acid of the ester, amide or nitrile employed. Preferably, an excess of alkali metal monohydrogen phosphate is included, so as to prevent an excessive decrease in pH during the reaction. For example, an excess of 10 to 200 mol per cent can be suitably employed.

The concentration of the alkali metal monohydrogen phosphate in the aqueous solution of the reaction mixture is limited only by the solubility of the salts therein at the reaction temperature. To insure a satisfactory rate of reaction, the concentration of the alkali metal monohydrogen phosphate should not be substantially less than 10%, and is preferably not less than 30% in the aqueous portion of the reaction mixture at the beginning of the reaction. Preferably, a sufficient amount of the alkali metal monohydrogen phosphate is used to maintain a concentration of at least 10% thereof in the aqueous portion of the reaction mixture until the end of the reaction.

The dehydrohalogenation is carried out by heating the reaction mixture at temperatures from about 60° to the boiling point of the mixture, e. g. to about 110° C. At these temperatures, the reaction is ordinarily complete within 1 to 5 hours. Higher temperatures (e. g. up to 150° C.) can be employed by applying sufficient pressure to maintain the mixture in the liquid phase.

The reaction is conveniently carried out by heating the dehydrohalogenation mixture under

reflux. By virtue of the absence of alkaline-reacting compounds during all or nearly all of the reaction, substantially no saponification of the dihalopropionic acid compound or the corresponding α -haloacrylic acid derivative occurs, despite the presence of substantial amounts of water. When the α -haloacrylic acid compound produced is volatile, it is advantageously recovered by distillation from the reaction mixture together with water, from which it can be separated, and subsequently purified by further distillation. The phosphates present in the reaction mixture are non-volatile and cause no contamination of the product. When the α -haloacrylic acid compound produced is relatively non-volatile, so that distillation is inconvenient, the product can be recovered from the reaction mixture by extraction with a volatile organic solvent, and recovered from the extract in known manner. The insolubility of the phosphates of the reaction mixture in organic solvents again prevents contamination of the products with these reagents.

The process is preferably applied to α,β -dihalopropionic acid esters, especially α,β -dichloropropionic acid esters for the preparation of the corresponding α -haloacrylic acid esters. The lower esters are volatile, and can be readily recovered from the reaction mixture by distillation.

Since the α -haloacrylic acid esters, amides and nitriles produced in the process of the invention are susceptible to polymerization, it is generally desirable to include a small amount of a polymerization inhibitor such as tertiary butyl catechol, hydroquinone, *p*-phenylene diamine, picric acid, copper or copper compounds in the reaction mixture, and to shield the mixture from actinic light, in order to avoid polymerization of the products. It is also of advantage to carry out the reaction in an atmosphere of an inert gas such as nitrogen.

The process of my invention is illustrated by the following examples, wherein the parts are by weight unless otherwise indicated, and parts by volume mean the volume occupied by an equal number of parts by weight of water.

Example 1

628 parts (4 mols) of methyl α,β -dichloropropionate containing 3 parts of picric acid (a polymerization inhibitor) dissolved therein, were heated to 50° C., and added to 1575 parts (4.4 mols) of melted disodium hydrogen phosphate dodecahydrate at 50° C. The mixture, preferably maintained under an inert atmosphere of nitrogen and shielded from actinic light, was agitated and heated at 90° C. for 2 hours under reflux.

At the conclusion of the reaction, the mixture was allowed to separate into two layers, and the lower aqueous layer was removed. The upper organic layer was distilled, yielding 244 parts of methyl α -chloroacrylate, while 221 parts of methyl α,β -dichloropropionate remained as a higher boiling residue. These results correspond to a conversion of 52% of the methyl α,β -dichloropropionate and a yield of methyl α -chloroacrylate amounting to 78% of theory.

Example 2

A solution of 1320 parts (9.3 mols) of anhydrous disodium hydrogen phosphate in 2000 parts of water was added to a mixture of 1295 parts (8.3 mols) of methyl α,β -dichloropro-

pionate containing 6.5 parts of picric acid, with 1000 parts of water. The reaction mixture was agitated under reflux for 3 hours at 66 to 74° C., preferably while maintaining an inert nitrogen atmosphere and shielding the reagents from actinic light. At the end of the aforesaid period, the reaction mixture was separated as in the preceding example, and the organic liquid layer distilled, whereby 623 parts of methyl α -chloroacrylate and 239 parts of unreacted methyl α,β -dichloropropionate were recovered. These results correspond to a 62% conversion of the methyl α,β -dichloropropionate, and a yield of methyl α -chloroacrylate corresponding to 76% of theory.

Example 3

157 parts (1 mol) of methyl α,β -dichloropropionate containing 1.7 parts of tertiary butyl catechol as a polymerization inhibitor were added to a solution obtained by neutralizing 140 parts by volume of 85% phosphoric acid (2.05 mols) with 160 parts (4 mols) of sodium hydroxide in 500 parts of water. The pH of the resulting aqueous solution was 6. The mixture was agitated and heated to boiling temperature under reflux while protected from light and air as in the preceding examples. At the end of this period, the pH of the aqueous solution in the reaction mixture was between 4 and 5. The mixture was separated into aqueous and organic layers, and the latter distilled as in the preceding examples. 91 parts of methyl α -chloroacrylate and 18 parts of methyl α,β -dichloropropionate were thus recovered, corresponding to a conversion of 75% and a yield of methyl α -chloroacrylate of 85% of theory.

Example 4

157 parts (1 mol) of methyl α,β -dichloropropionate containing 1.7 parts of tertiary butyl catechol as a polymerization inhibitor, were mixed with a solution obtained by neutralizing 210 parts by volume of 85% phosphoric acid (3.08 mols) with 240 parts (6 mols) of sodium hydroxide in 500 parts of water. The pH of the aqueous solution was 6. The reaction mixture, protected from light and air as in the preceding examples, was heated at boiling temperature under reflux and agitated for 1 1/4 hours. At the end of this period, the pH remained about 6. The mixture was then worked up as described in the preceding examples, yielding 64 parts of methyl α -chloroacrylate and 37 parts of methyl α,β -dichloropropionate, corresponding to 53% conversion and 70% of theoretical yield of methyl α -chloroacrylate.

The phosphates employed for dehydrohalogenation in accordance with this invention are the alkali metal (sodium or potassium) monohydrogen phosphates, including alkali metal ammonium monohydrogen phosphates.

The concentration and proportions of these salts in the reaction mixture, and the temperatures disclosed in the examples can be varied within the ranges discussed above to obtain similar dehydrohalogenation results. The aqueous solution containing the aforesaid alkali metal monohydrogen phosphate has a pH of 4 to 8, and preferably between 4 and 7, throughout practically all of the reaction, by reason of the formation or presence therein of alkali metal dihydrogen phosphates. The preferred pH range during the reaction is 5 to 6. (The pH values and ranges referred to herein are those determined at 25° C.)

The esters to which the process illustrated above can be applied are the esters of α,α - and α,β -dichloro-, -dibromo- and -diiodopropionic acids, but the process is most conveniently applied to esters of α,β -dichloropropionic acid. Such esters include the alkyl esters, e. g. methyl, ethyl, isopropyl, butyl, amyl, isoamyl, n-hexyl, octyl, lauryl and octadecyl esters of the aforesaid acids. In addition, there may be mentioned the corresponding alkenyl esters, such as allyl, methallyl, crotyl, oleyl and chloroallyl esters. The process can also be applied to polyhydric alcohol esters of the aforesaid acids, e. g. to the glycol, glycerol, sorbitol and mannitol esters, as well as to the aryl, aralkyl, cycloparaffinic and heterocyclic esters such as, for example, the phenyl, cresyl, resorcylic, naphthyl, benzyl, fenchyl, cyclohexyl and furfuryl esters. All of these esters yield the corresponding α -haloacrylic esters upon dehydrohalogenation by the procedure disclosed above and illustrated in the examples. Moreover, the procedure of this invention is not only applicable to the esters of the aforesaid α,α - and α,β -dihalopropionic acids, but also to the corresponding nitriles, amides and N-mono- and disubstituted amides in which the nitrogen substituents can be aliphatic, araliphatic, cycloaliphatic, aromatic, or heterocyclic, as for example, the mono- and dimethylamides, mono- and diethylamides, the β -hydroxyethylamides, the cyclohexyl- and cyclohexylmethylamides, the benzyl- and benzylmethylamides, the anilides, the morpholides or piperides of α,β -dichloropropionic acid. These compounds, like the esters, yield the corresponding α -haloacrylic acid compounds by the same procedure as that employed for the esters of these acids.

Variations and modifications which will be obvious to those skilled in the art can be made in the specific procedures disclosed above without departing from the scope or spirit of the invention.

I claim:

1. A process for the preparation of an ester, amide, or nitrile of an α -haloacrylic acid, which comprises dehydrohalogenating a member of the group consisting of the esters, nitriles, amides and N-substituted amides of dichloro-, dibromo-, and diiodo-propionic acids containing at least one of its substituent halogens in α - position, by heating in the presence of an aqueous solution of an alkali metal monohydrogen phosphate, having a pH not exceeding 8.

2. A process for the preparation of an ester, amide, or nitrile of an α -haloacrylic acid, which comprises dehydrohalogenating a member of the group consisting of the esters, nitriles, amides and N-substituted amides of dichloro-, dibromo-, and diiodo-propionic acids containing at least one of its substituent halogens in α - position, by heating in the presence of an aqueous solution of an alkali metal monohydrogen phosphate, further containing an alkali metal dihydrogen phosphate, the pH of said solution being between 4 and 7.

3. A process for the preparation of an ester, amide, or nitrile of an α -haloacrylic acid, which comprises dehydrohalogenating a member of the group consisting of the esters, nitriles, amides and N-substituted amides of dichloro-, dibromo-, 70

and diiodo-propionic acids containing at least one of its substituent halogens in α - position, by heating in the presence of an aqueous solution of an alkali metal monohydrogen phosphate, further containing an alkali metal dihydrogen phosphate, the pH of said solution being between 4 and 7, wherein the concentration of said alkali metal monohydrogen phosphate is maintained at at least 10% throughout the reaction.

10 4. A process for the preparation of an ester, amide, or nitrile of an α -haloacrylic acid, which comprises heating a mixture of 1 mol of a member of the group consisting of the esters, nitriles, amides and N-substituted amides of dichloro-, dibromo-, and diiodo-propionic acids having at least one of its substituent halogen atom in α - position, with an aqueous solution having a pH of 4 to 8 and containing 1 to 3 mols of an alkali metal monohydrogen phosphate in a concentra-

15 tion of at least 10% at a temperature from 60 to 110° C.

16 5. A process for the preparation of an ester of α -chloroacrylic acid, which comprises heating the corresponding ester of α,β -dihalopropionic acid at a temperature from 60 to 110° C. with an aqueous solution of an alkali metal monohydrogen phosphate together with an alkali metal dihydrogen phosphate, said solution having a pH between 4 and 7, and the concentration of said alkali metal monohydrogen phosphate being at least 10% throughout the reaction.

17 6. A process for the preparation of methyl α -chloroacrylate, which comprises heating methyl α,β -dichloropropionate at a temperature from 60 to 110° C. with an aqueous solution of an alkali metal monohydrogen phosphate together with an alkali metal dihydrogen phosphate, said solution having a pH of 5 to 6, the concentration of said alkali metal monohydrogen phosphate being initially at least 30% and the amount thereof being sufficient to maintain the concentration thereof above 10% throughout the reaction.

18 7. A process for the preparation of methyl α -chloroacrylate, which comprises adding methyl α,β -dichloropropionate to a solution in water of disodium hydrogen phosphate amounting to 1 to 3 mols per mol of α,β -dichloropropionate, the concentration of said phosphate in said solution being at least 30%, and heating the reaction mixture at 60 to 110° C.

19 8. A process for the preparation of methyl α -chloroacrylate, which comprises adding methyl α,β -dichloropropionate to a solution in water of sodium monohydrogen phosphate together with a minor amount of sodium dihydrogen phosphate in sufficient amount to yield a pH below 7, the concentration of said disodium hydrogen phosphate being initially at least 30%, and the amount thereof at least sufficient to maintain the concentration above 10% throughout the reaction.
